F. J. COLE.
BRAKE BEAM FOR RAILROAD CARS.

3 Sheets—Sheet 3.

No. 503,263.

Patented Aug. 15, 1893.

UNITED STATES PATENT OFFICE.

FRANCIS J. COLE, OF BALTIMORE, MARYLAND.

BRAKE-BEAM FOR RAILROAD-CARS.

SPECIFICATION forming part of Letters Patent No. 503,263, dated August 15, 1893.

Application filed April 11, 1893. Serial No. 469,945. (No model.)

To all whom it may concern:

Be it known that I, FRANCIS J. COLE, a citizen of the United States, and a resident of Baltimore city and State of Maryland, have ⁵ invented certain new and useful Improvements in Brake-Beams for Railroad-Cars, of which the following is a specification.

My invention relates to an improvement in ¹⁰ brake-beams used in applying the brake-shoes or rubbers to wheels of railroad cars and other rolling stock, and provides a strong rigid trussed-beam, which can be easily and cheaply constructed and through which the braking-force applied through the brake-lever can be ¹⁵ transmitted to the wheels with but little deflection or lost motion. Heretofore brake-beams have been made in many different forms of greater or less complication. The ²⁰ great desideratum in a brake-beam is simplicity, strength and cheapness of construction. These objects I attain by making a beam of rolled angle-iron of various shapes, securing a malleable iron head upon both ends and bracing the two ends of the beam by a ²⁵ suitable truss-rod and a bifurcated king-strut.

The novel features of my invention consist of the use of straight sections of angle-iron or steel of varying shapes, (I or U shapes being ³⁰ preferred) as the brake-beam east-heads secured to the extremities thereof, to which the brake-shoe-heads may be directly bolted in the usual manner; a truss-rod secured to the brake-beam-head at a point between the ³⁵ brake-shoe-bolts and the king-strut, so as to leave a clear passage for the brake-shoe-bolts in the extremities of the brake-beam-heads. The truss-rods are secured to the brake-beam-heads and the king-post or strut in various ways. The bifurcated king-post or strut ⁴⁰ serves a double purpose, that of separating the compression-member and the extension-member, and upon which the strain is distributed, and also the purpose of carrying a bearing for the brake-lever which passes through ⁴⁵ the center of said strut. This strut is constructed in a peculiar manner; it is seated at the end next the truss-rods in a socket in which it will turn, but which is provided with clamping-devices by which it may be rigidly ⁵⁰ fixed in the socket at any desired angle. The end next the brake-beam is secured to the brake-beam by means of a bolt which, when

tightened, will lock that end firmly to the brake-beam.

One of the advantages of my structure is ⁵⁵ that the beam may be taken to pieces and the parts used in other connections or a broken part replaced or the parts may be readjusted by tightening up the struts.

In the drawings Figure 1 is a plan view of one ⁶⁰ form of brake-beam and truss-rod. Fig. 2 is a top view of the same. Fig. 3 is a vertical section of the brake-beam and truss-rod, showing a full side-elevation of the king-strut. Fig. 4 is a plan view of a different form of brake-⁶⁵ beam, brake-beam-head, truss-rod-attachment and means for securing the same to the king-strut. Fig. 5 is a bottom view of the brake-beam-head and a portion of the brake-beam and truss-rod. Fig. 6 is still another modified ⁷⁰ form of the brake-beam-head and means of attaching the truss-rod to the same. Fig. 7 is a bottom view of the same. Fig. 8 is a plan view of another form of brake-bar and head, the brake-bar being composed of a U-shaped ⁷⁵ channel-iron. Fig. 9 is a section of the channel-iron used in Fig. 8. Fig. 10 is a sectional view of the channel-iron and head or block. Fig. 11 is a vertical section of the end of the ⁸⁰ brake-beam and head, and side-elevation of the brake-head and shoe, showing the means of attachment of the brake-head to the beam. Fig. 12, is a plan view of another modified form of beam and head and showing a modified method of introducing the truss-rod. Fig. 85 13 is a rear view of the same. Fig. 14 is a side elevation of the king-strut showing the brake-beam and truss-bar in section.

Referring to Fig. 1 A represents the brake-beam made of a piece of "I" shaped iron; this beam is generally made straight; if desired, however, it may be bent a little in the center; on either end of the brake-beam there is placed a malleable iron head B into which the beam A fits; the head B is perforated as shown ⁹⁰ in Fig. 2 with two bolt-holes b', at right angles to its front and rear surfaces, the other b² at an angle of about forty-five degrees; it is also provided on its upper side with a boss or lug b³ through which the diagonal hole ⁹⁵ passes.

C is the king-strut or post, which is bifurcated in its center at D, but said bifurcation is closed at both ends. At its upper end it is

perforated and through the hole thus formed a bolt E passes and also through a hole in the center portion of the "I" iron of the brake-beam. By this hole the king-strut may be rigidly secured to the brake-beam at its upper end. The strut is constructed in two parts, the bifurcated portion C-C' and a socket portion F; the lower end of the portion C is made round and fits the socket F; the socket F' is split on one side at G and provided with two lugs H-H on its upper edge on either side of the split in socket. Through the lugs H-H passes a bolt I, by the tightening of which the socket may be rigidly clamped upon the lower end of the king-post. Through the centers of the two portions of the king-posts C and C' are holes J-J which form bearings for the pivot of the brake-lever. It will be observed that, when the bolts E and I are loosened the king-post may be rotated upon its axis and placed at any desired inclination, thus giving any desired angle to the brake-lever; the bolts E and I may then be screwed up and the post clamped rigidly in the desired position.

K is the truss-rod which passes through a hole in the bottom of socket F and the ends pass through the inclined holes b² in the ends of the brake-beam and are held in place by nuts screwed upon its extremities, which bear upon the lugs b³ on the brake-beam heads. It is a matter of primary importance that the truss-rods K should be secured to the brake-beam-heads at such a point as to leave the extremities of the beam-heads free to receive the bolts by which the brake-shoe-heads are bolted to them.

Referring to Fig. 4, the form of brake-beam-head B² shown in that figure differs from that of Fig. 1 and the truss-rods K' also differ somewhat in their method of attachment to the brake-beam-head and also to the foot of the king-post. In this case the brake-beam-head is not perforated entirely through by a hole for the truss-rod, but is simply provided with a socket on its front side into which the head of the truss-rod fits and which is cut away on the upper side so that the brake-beam A may enter the head above the head of the truss-rod, and thus the perforation of the brake-beam for the passage of the truss-rod is avoided. The truss-rod is divided into two parts, and nuts are screwed upon the ends k²-k² where they pass through holes in a casting F' on the lower end of the socket F of the king-post.

Fig. 5 is a bottom view of the structure shown in Fig. 4.

Fig. 6 shows a still further modified form in which the brake-beam-head B² is perforated with a socket k³. The truss-rod K' passes into the head through a hole k⁴ and into the socket k³ where it is screwed into a nut k⁵ which has been placed in said socket. Fig. 7 is another view of the same.

Fig. 8 shows the brake-beam made of a "U-shaped" channel-iron, shown in section

in Fig. 9, preferably pressed or struck up out of plate steel. The brake-beam-head B⁴ consists of a block which is fitted into the "U" 70 or channel-iron, filling the same, and which is bolted to the channel-iron by bolts b⁶-b⁵. The head B⁴ is shown in section in Fig. 10. In the rear side of said block is a notch b⁶ and from it a perforation b⁷ passes through the end of the block, through which passes the truss-rod K². In this case as in all other forms, the truss-rod is secured to the head B⁴ at a point between the center of the brake-beam and the point where the bolt for the 80 brake-head passes through the brake-beam-head.

Figs. 12, 13 and 14 show still another modified form of brake-beam, which consists of two parallel bars of metal which constitute 85 the compression-member, and which may be bolted together if desired.

In this specification the caps or fillings on the ends of the brake-beams are called the brake-beam-heads. The truss-rods, sometimes one rod and sometimes two rods, are called truss-rods; and the portion of the brake-shoe which is secured to the beam-heads are called brake-shoe-heads.

An important feature of my brake-beam is 95 the simplicity of the combination of a piece of straight rolled iron, a head and a bolt through the head by which to secure the brake-head in the same way in which it has been heretofore secured to a wooden beam. 100 My beam becomes a complete substitute for the wooden beam from this fact, while the straight piece of rolled iron gives the requisite strength and the head a sufficient body of metal to which to attach the truss-rod and the brake-head.

What I claim is—

1. In a brake-beam the combination of a brake-beam, truss-rods and king-post, the king-post consisting of two parts, a post and a socket therefor, said socket being provided with means for rigidly clamping the post in the socket in any desired position.

2. In a brake-beam the combination of a brake-beam, truss-rods and king-post, said king-post being constructed in two parts, a post and a socket, said socket being provided with means for clamping it upon the post in any desired position, the other end of said post being secured to the brake-beam by 115 means of an axial bolt, which may be loosened and tightened to allow a change of position of the king-post and its rigid fixation in any desired position.

3. In a brake-beam the combination of a 125 brake-beam consisting of a "U-shaped" channel-iron, a king-post secured to the center of the brake-beam, and a truss-rod secured to the two ends of the brake-beam and passing over the extremity of the king-post.

4. In a brake-beam the combination of a 130 brake-beam consisting of a "U-shaped" channel-iron, a head secured to either end thereof, a king-post secured to the center of the

brake-beam, and a truss-rod secured to the two heads of the brake-beam and passing over the extremity of the king-post.

5. In a brake-beam the combination of a
brake-beam consisting of a "U-shaped" channel-iron, a head secured to either end thereof, consisting of a block of metal fitting the channel-iron and filling the space between the walls thereof.
10. 6. In a brake-beam the combination of a
brake-beam, a head secured to either end thereof, a king-post secured to the center of

the beam and truss-rods, provided with heads or nuts on one end which are secured in sockets in the under sides of the beam-heads, the 15 other ends of which pass through the lower end of the strut and are secured thereto by nuts.

Signed at Baltimore city and State of Maryland this 27th day of March, A. D. 1893.

FRANCIS J. COLE.
